UNITED STATES PATENT OFFICE.

FRANK S. BENNETT, OF PHILADELPHIA, PENNSYLVANIA.

EYE-PROTECTOR.

SPECIFICATION forming part of Letters Patent No. 583,590, dated June 1, 1897.

Application filed August 21, 1896. Serial No. 603,522. (No model.)

To all whom it may concern:

Be it known that I, FRANK S. BENNETT, a citizen of the United States, residing at Philadelphia, in the county of Philadelphia and State 5 of Pennsylvania, have invented a certain new and useful Improvement in Eye-Protectors, of which the following is a specification.

My invention relates to a new and useful improvement in eye-protectors, and has for 10 its object to provide a simple, cheap, and efficient device by means of which dust, rain, and snow may be prevented from coming in contact with a person's eyes and yet leaving the eyes of such a person free to observe as though 15 no protector were used.

With these ends in view my invention consists in the details of construction and combination of elements hereinafter set forth, and then specifically designated by the claim.

20 In order that those skilled in the art to which this invention appertains may understand how to make and use the same, its construction and operation will now be described in detail, referring to the accompanying drawings, forming a part of this specification, in which—

Figure 1 represents the application of my improvement, and Fig. 2 is a front elevation of the same.

30 In carrying out my invention I mold or shape transparent celluloid into certain contours best adapted for fitting the form of the face adjacent the eyes of a person, and that part of the device which comes immediately in front of the eyes is concaved and convexed, as indicated at A, the convexity lying outward. The center portion of the device is 35 preferably made to fit the nose, as indicated at B, in which case this point will serve to

40 center the device upon the face and prevent it from slipping sidewise. C are holes, which may be eyelets in projections at the ends of the protector, and are for the purpose of attaching a cord or elastic D to secure the device upon.

45 From this it will be seen that when a device

is attached over the eyes of a person no obstruction will be afforded to the clear view, and yet the eyes will be perfectly protected from dust or other elements. This is true from 50 the fact that the entire protector is composed of transparent material and does not require an opaque frame to support any part thereof, thus leaving the view entirely unobstructed.

One of the advantages of my improvement 55 is that it, being made of celluloid or other like transparent flexible material, has but little weight and is not objectionable to the wearer. Another advantage of my improvement is being made of a single piece of such material 60 as may be readily molded or otherwise shaped. The cost of a protector is exceedingly small, and it may therefore be utilized by all classes of persons who require the use of an eye-protector. 65

My improvement is especially advanta- 70 geous for use by the motormen of electric-railway cars as well as brakemen upon steam-railway trains, and when not temporarily in use it may be folded into a small compass and carried in the pocket.

Having thus fully described my invention, what I claim as new and useful is—

An eye-protector consisting of a transpar- 75 ent piece of celluloid two concavo-convex por- tions formed thereon adapted to fit over the eyes, flat portions surrounding said concavo-convex portions molded to conform to the shape of the face, the center portion thereof being formed into a ridge to fit over the upper part of the nose, projections formed at the ends of said protector, said projections having eyelets secured therein, an elastic cord secured through said eyelets, substantially 80 as described. 85

In testimony whereof I have hereunto af- fixed my signature in the presence of two sub- scribing witnesses.

FRANK S. BENNETT.
